UNITED STATES PATENT OFFICE

2,642,214

BOTTLE FILLER

Adolph J. Lippold, Milwaukee, Wis., assignor to
Cherry-Burrell Corporation, Chicago, Ill., a corporation

Application October 21, 1947, Serial No. 781,193

1 Claim. (Cl. 226—96)

1

This invention pertains to improvements in a bottle filler or the like. More particularly, this invention pertains to the bottle lifters and the lifter support for an automatic rotary type bottle filler.

The objects of this invention include the provision of a relatively simple, inexpensive bottle lifter and bottle lifter support of sanitary design, wherein all moving parts are readily accessible for inspection and repair.

Rotary type bottle fillers of conventional design are commonly provided with a turntable for carrying the bottle supports or pedestals. In most instances, such turntables are mounted closely adjacent to and overlap a sizable portion of the base or frame of the bottle filler apparatus. Such construction renders thorough cleaning of the apparatus difficult and hinders inspection.

In many rotary types of automatic bottle fillers, the individual bottle lifters or pedestals carried thereon are relatively complicated, and, in many instances, the lifters are not removable without a major disassembly of the apparatus. Obviously, such design does not lend itself well to relatively simple and rapid repair or adjustment of the bottle supports of such a filler.

The primary objects of this invention include the provision of an improved design for bottle lifters and lifter support for bottle fillers; in which the lifters and lifter support are of sanitary design; in which the operating elements of the bottle lifter and bottle lifter support may be readily inspected, cleaned or repaired; and in which the operating element of the bottle lifter may be readily removed for inspection or adjustment.

The foregoing and other objects and advantages of this invention will become more apparent and will be more readily understood when considered in connection with the drawings of the preferred embodiment of the present invention, which, without desire of limitation, will be described and illustrated as improvements in the bottle lifters and bottle lifter support for a rotary type of bottle filler.

In the accompanying drawings:

Figure 1 is a partial, side elevational view of a bottle filler, embodying the applicant's invention in improved bottle lifters and bottle lifter support.

Figure 2 is a plan view of the improved bottle lifter support.

Figure 3 is a sectional elevation, taken along line 3—3 of Figure 2 of the drawings.

Figure 4 is a view, partially in section, taken along line 4—4 of Figure 2 of the drawings.

2

Figure 5 is a view of a modified form of bottle guard ring, which may be substituted for the form of guard ring illustrated in Figure 4 of the drawings.

5 Figure 6 is a side, elevational view, partially in broken-away section, of the improved bottle lifter.

Figure 7 is a front, elevational view, partially in broken-away section, of the improved bottle lifter.

10 Figure 8 is a view, partially in section, taken along line 8—8 of Figure 7 of the drawings.

Referring to the drawings, in which like elements are identified by like numerals, 1 represents the frame of a bottle filler and capper, having a vertically extending, rotatably mounted filler bowl spindle 2, upon which the circular filler bowl 3 is concentrically mounted, and adapted to rotate in unison with the spindle 2.

15 In a conventional manner, the filler bowl 3 is provided in its lower wall with a suitable number of filler heads 4, positioned near the outer lower edge of the bowl 3. A hub 5 of the bottle lifter support or base 6 is mounted on and keyed to the spindle 2 for the rotation of the support 6 in unison with the rotation of spindle 2 and filler bowl or supply tank 3. The support 6 for the bottle pedestals consists primarily of the central hub 5, a plurality of spokes 7, fixed at their inner ends to the hub 5 and extending outwardly therefrom, and a circular rim 8, affixed to the outer ends of the spokes 7. Rim 8 is thus supported concentrically with the rotary spindle 2. The circular rim 8 is provided on its outer periphery with a plurality of uniformly spaced bottle lifters or supports 9. The bottle pedestals or standards 9 are of sectional construction formed of two closely fitted, telescoped sections of rectangular tubing 10 and 11, which are of such dimensions as to be in close sliding contact one with another. The inner or lower telescoped section 10 of each of the lifters 9 is welded along the lower portion of its inner face to the outer periphery of the rim 8. The outer telescoped section 11 of the bottle standard 9 is provided at its upper end with a closure or bottle support plate 12, securely fixed thereto by any desired method such as by welding, or may be formed integrally therewith.

20 Two compression spring guide rods 13 are fixed as by welding to the lower surface of the plate 12 and extend downwardly into the telescoped tubular sections 10 and 11. Compression springs 14 are mounted on the spring guide rods 13 and are partially compressed intermediate the plate 12 and the apertured spring compression element 15. Compression element 15 is telescoped over the free ends of the associated spring guide rods 13

a sufficient distance to permit the spring clip 16 to be fitted into the spring clip grooves 17 in the outer face of the lower free ends of the spring guide rods 13.

As will be obvious upon an inspection of Figure 7 of the drawings, the springs 14, the spring compression element 15, and the spring clip 16 may all be assembled onto the spring guide rods 13 prior to the telescoping of the upper sectional element 11 of the bottle lifter 9 onto the lower sectional element 10 of the bottle lifter 9. The maximum expansion of the springs 14 on the guide rods 13 is limited by the engagement of the spring compressor plate 15 and the spring clip 16.

To support the upper sectional element 11 of the telescoped sectional bottle lifter or support 9 in maximum elevated position when the springs 14 are expanded, there are provided bumper plates 18 affixed to the interior surface of the lower portion of the lower section 10 of the sectional lifter 9. The cam follower 19, carried by the outer sleeve 11 of the bottle lifter 9, upon the application of a sufficient pressure to compress springs 14, such as would occur when the cam follower 19 is forced to roll through below the cam track 20, may lower the bottle support plate 12 to a suitable bottle receiving or discharge elevation. Upon the lowering of the bottle support plate 12 by the application of pressure either to the plate 12 or to the cam follower 19, springs 14 will be compressed in proportion to the pressure thus applied.

When the springs 14 are compressed, the lower ends of the spring guide rods 13 will be telescoped downwardly through the spring compression plate 15, which compression plate is held in position by the bumper plates 18. Upon the release of the pressure upon the bottle plate 12 or the cam follower 19, the springs 14 will immediately elevate the upper sectional element 11 of the sectional bottle lifter 9 until the spring clip 16 again engages the spring compression plate 15 to thereby limit further expansion of the springs 14.

In the operation of a bottle filling device of the type contemplated by this invention, it sometimes happens that a bottle or similar receptacle, due to improper placement on the bottle lifters, may fall from the pedestal into the spider-like framework of the rotatable bottle support 6. To prevent such a bottle from falling through between the spokes 7 of the support 6, with the possible result that the bottle may be jammed between a spoke 7 and a stationary part of the framework 1 of the bottle filler, guard rings 21 have been provided. The guard rings 21, which may be of any desired number, are supported upon the spoke 7 and are arranged concentric with the hub 5 and may be of the form shown in Figure 4 of the drawings, in which the portion of the rings 21 overlapping a spoke 7 is crimped downwardly over the adjacent portion of the spoke 7. An alternative form of guard ring is shown in Fig-

ure 5 of the drawings, in which the ring 22 is welded or otherwise suitably attached to the adjacent portion of the spoke 7.

Having thus described and illustrated the preferred embodiment of the present invention in improved bottle lifters and bottle lifter support, adapted for use in connection with a bottle filler or like device, the invention is not to be restricted to the specific embodiment thereof, as illustrated in the drawings and as hereinbefore described, excepting insofar as may be necessary in view of the appended claim.

I claim:

In a receptacle filling device of the class described, the combination of a base, an outwardly extending bracket member rotatably mounted thereon and adapted to be rotated therearound in a substantially horizontal plane, a receptacle holder secured to the outer extremity of said bracket, and a container mounted over said bracket and adapted to rotate therewith, said receptacle holder comprising a substantially vertically disposed elongated support body having a downwardly extending longitudinal opening therein, a receptacle carrier having a downwardly depending sleeve telescopically engaged in vertical slidable relation on said elongated support body, a stem depending downwardly from said carrier within said sleeve and projecting into the longitudinal opening of said elongated support body, an enlargement at the end of said stem remote from the carrier, a seat slidably engaged on said stem and held against removal therefrom by said enlargement, a resilient member interposed between said carrier and said seat and adapted to cause the latter to bear against said enlargement, a shoulder in the longitudinal opening of said support body adapted to support said seat at a predetermined level therein, and an external projection on said sleeve, said receptacle filling device having fixed retracting means disposed outwardly from said bracket member and adapted to engage said external projection at a selected location in the path of rotation of said bracket to bear downwardly thereon to retract said receptacle carrier.

ADOLPH J. LIPPOLD.
